MATERIAL HANDLING MECHANISM

Eugene W. Steele, Sewaren, and Fernando A. Morin, Fords, N. J., assignors to American Smelting and Refining Company, New York, N. Y., a corporation of New Jersey

Application January 7, 1936, Serial No. 57,891

10 Claims. (Cl. 214—11)

By the present invention there is provided an improved type of material handling mechanism or conveyor which is adapted to serve as an inspection table for facilitating the inspection of 5 metal castings and for segregating imperfect castings from those fulfilling desired specifications or requirements for further working.

While the mechanism is of general applicability, it will be illustrated and described specifically in 10 connection with the handling of copper wire-bar castings for enabling the ready inspection thereof and the ready isolation of such bars as may be determined from inspection as requiring treatment for removal of surface imperfections or for 15 other defects of a nature rendering such castings unsuitable for direct marketing.

It is the customary procedure in the casting of the wire-bars to pour the copper after a suitable refining treatment from the furnace into the 20 wire-bars molds in which the castings solidify. The molds are coated with a bone ash mold dressing, some of which may become included in the castings, or there may develop excrescences of molten metal on the outer surfaces of the castings, or irregularities in the surfaces of the castings may arise from other causes; and such irregularities must be removed before the wire-bars are sent to the rolling mill.

In accordance with the usual practice, the wire-bars are dumped from the molds into a tank filled 30 with water, in which they are quenched and from which they are picked up by a conveyor entering the tank. Upon being discharged from the conveyor the wire-bars are inspected by operators 35 and so far as possible the surface imperfections are removed by dressing the bars with suitable tools, such as for instance, pneumatic chisels or chipping tools. Of course, the conveyor removes the wire-bars from the quenching tank and discharges them indiscriminately regardless of the 40 degree of dressing which may be required, and regardless of whether or not the castings are of such character as may be sent directly to the rolling mill or required remelting and recasting 45 in order to fulfill the rolling mill requirements. In view of the fact that the wire-bars are comparatively heavy, i. e., from 225 up to 400 pounds each, the separation of the marketable from the unmarketable bars has entailed a considerable 50 amount of laborious handling, and the inspection and separation of the rejected bars requires a considerable amount of handling and the attendance of several operators or lifters for removing the bars from the conveyor as they are brought up from the quenching tank and placing them on

suitable inspection tables. This handling, obviously, introduces an additional hazard factor.

One of the objects of the present invention is to provide a conveyor or inspection table which will minimize the amount of manual handling of 5 the bars, thereby reducing the degree of hazard and the amount of labor entailed in the inspection thereof.

A further object of the invention is to provide an inspection table which will enable the ready 10 separation of the rejected bars from those satisfactorily passing inspection.

A still further object of the invention is to provide an inspection table in which the inspected bars, both those of a satisfactory character and 15 those under rejection, are brought to unloading points and deposited in position for removal from the table with the minimum of handling.

A still further object of the invention is to provide an inspection table on which the castings 20 are conveyed to a discharge point and on which the castings may be dressed during their transit along the conveyor.

Further objects and advantages of the present 25 invention will become apparent as the description proceeds, and the features of novelty will be set forth specifically in the appended claims. The invention accordingly comprises the features of construction, combination of elements, and arrangements of parts, which will be exemplified in 30 the construction hereinafter set forth and the scope of the application of which will be indicated in the claims.

The present invention will be more readily understood by reference to the accompanying drawings, in which

Fig. 1 is a plan view of the improved conveyor and inspection table.

Fig. 2 is a side elevation thereof.

Fig. 3 is a sectional elevation taken on the line 40 3—3 of Fig. 1, looking in the direction of the arrows, and showing the positions of the cross or auxiliary conveyor.

Fig. 4 is a sectional elevation taken on the line 45 4—4 of Fig. 1 looking in the direction of the arrows.

Fig. 5 is a sectional elevation taken on the line 50 5—5 of Fig. 2, looking in the direction of the arrows.

Referring more particularly to the drawings, it will be seen that the inspection conveyor comprises, in effect, a plurality of sections A, B and C.

Section A is an inclined conveyor which is adapted to bring the wire-bars to the inspection conveyor section B, and to position the said wire- 55

bars on the conveyor B in substantially parallel and equi-spaced relation, whereby the wire-bars will be readily accessible for inspection and chipping as they travel along the conveyor to the discharge end thereof. The conveyor A receives the wire-bars from an inclined chute D, onto which chute the wire-bars are discharged from a bosh conveyor E, which brings the wire-bars from the quenching tank, not shown.

10 The conveyor A comprises sprockets 7 and 9, three of each being illustrated, although the number may be increased or diminished according to the number of conveyor chains desired to be used. The sprockets 7 are mounted on a common shaft 11 and sprockets 9 are mounted on a common shaft 13. Shaft 11 turns in bearings 15 mounted on the supporting angle-frame 17, and the shaft 13 turns in bearings 19 also mounted on the angle-frame 17.

15 The conveyor itself comprises endless chains 21, three of which are shown, which pass over the sprockets 7 and 9. These chains carry equi-spaced upstanding dogs 23 which preferably have rounded surfaces 25 for engaging the wire-bars, the outlines of which are indicated by dotted lines as shown at 27. Guide plates 29 and 31, mounted on angles such as shown at 33 and 35, converge towards the conveyor B, so that the ends of the wire-bars will come into engagement 20 with these guide plates, thereby shifting the wire-bars lengthways until their ends become in alignment, the wire-bars being transferred in this manner to the conveyor B.

25 The conveyor B comprises supporting frames 39 and 41 composed of suitable angles bolted or riveted together, and endless chains 43 and 45, which pass over the pairs of sprockets 47, 47 and 49, 49. The sprockets 47, 47 are mounted on a drive shaft 51 operating in bearings 53, 53, 40 while the sprockets 49, 49 are mounted on the shaft 11. The shaft 51 is provided with a drive sprocket 55 operated by a sprocket chain 57 which in turn is operated by a sprocket 59 on the drive shaft of a speed reducer 61 driven 45 by a motor 63. Therefore, the motor 63 drives both conveyors B and A.

30 Adjacent to the drive end of the conveyor B is a gravity transfer conveyor C, comprising a series of rollers 65, each of these series of rollers being mounted in side angles 67, 67, whereby the conveyor C is divided into sections as will become more clearly apparent hereinafter.

35 Cooperating with the conveyor C is a secondary or short conveyor F, which comprises endless conveyor chains 69, 69 which chains pass over driving sprockets 71, 71 mounted on the drive shaft 51, and tail sprockets 73, 73 mounted on a tail shaft 75 operating in bearings 77, 77 mounted on horizontal supporting beams 79, of a suitable 40 supporting framework. The secondary conveyor F is positioned above the normal level of the conveyor C, and the conveyor F operates at substantially right angles to the conveyor C as will be apparent.

45 The conveyor C, in addition to the rollers 65, comprises the bottom channels 81, 81, which are illustrated as being supported on base angles 83, 83, 83 (Fig. 3), which base angles are disposed at right angles to the channels 81. The 50 channels 81 are welded, at suitably spaced intervals, to upright angles 85, which upright angles are shown as being grouped in three groups of two pairs each of the angles, each group of the upright angles 85 supporting a pair of the side angles 67 in which the rollers 65 are mounted. It

55 will be seen further that upright angles 87, 87 and 89, 89 are welded to the base angles 83, and to these upright angles are welded the guide channels 91, 91, and 93, 93 which form guides and supports for the conveyor chains 43 and 45 of the main conveyor B, and also similar guide channels 95, 95 for the conveyor chains 69, 69 of the secondary conveyor.

60 It will be seen also that there is disposed a group of rollers 65, mounted in the manner above indicated, intermediate the respective conveyor chains, the channels 81, 81, forming a common mounting for the groups of rollers and their supporting structures. The upright angles 89 at the foot of the conveyor C carry rigid brackets 15 97, 97 and upright angles 99, 99, which are welded to the channels 81, 81, are pivotally connected to the brackets 97, 97 by a pivot shaft 101, the shaft 101 forming the axis about which the entire conveyor structure C pivots when it is lifted to 20 operative position as indicated by the dotted lines in Figs. 2 and 3.

25 Guide plates 86 mounted on angles 85 of conveyor C immediately within the limits of conveyor B act as guides to maintain the alignment 30 of conveyor C at substantially right angles relative to conveyor B by contacting with angles 88 when the conveyor C assumes the dotted line position, the guides 86 enabling the conveyor C to 35 resist the pressure incident to engagement of bars moving thereagainst when the conveyor C is raised to operative position, such engagement being possible when the spacing of the bars 27 becomes unequal from any cause, or in the event 40 the bars become bunched on the conveyor B; and the guides 86 enable, further, the inspectors to separate the rejected bars from passable bars when the bars are bunched in this manner at the conveyor C, and to direct the rejected bars onto the conveyor C. 45

50 In order to accomplish the manipulation of the conveyor structure C, air cylinder 103 is provided, the upper end of the piston rod 105 of which has a head 107 pivotally connected by pivot shaft 109 with angles 111 welded to the underside of 55 the flanges of the angles 67. The piston rod 105 is operated by air pressure acting on a cup member 113, the air admission being controlled by a conventional three-way valve 115 which is operated by a handle 117, the valve 115 being connected with a suitable source of compressed air by means of a pipe 119, other pipes 121 and 123 connecting the valve 115 with the air cylinder 103. When air is admitted beneath the piston cup member 113, it lifts the member 113 and 55 the rod 105, thereby elevating the conveyor structure C into the dotted line positions of Figs. 2 and 3.

60 In passing, it may be noted that the supporting frame 39 of the main conveyor B comprises angle bars 127, which are welded to the upright support angles 129, and welded to these angles 129 are transversely extending angles 131. These angles 131 have welded thereto the I-beams 125, 125 which in turn support the guide channels 65 91, 91 of the conveyor chains. 65

65 The operation of the mechanism as illustrated will become clear from the above description when taken in conjunction with the following explanation:

70 Wire-bars 27 are picked up by flights 133 of the bosh conveyor E, being automatically carried by these flights 133 so that the wire-bars lie across the conveyor E. The conveyor E is operated by a drive sprocket 135 mounted on a head-shaft 137 75

and which is driven by a chain 139 from a suitable motor not shown. Conveyor sprockets 141 and 143 are also mounted on the shaft 137.

From the conveyor E, the wire-bars are dumped into the chute D, as indicated by the arrow 144 in Fig. 2. The chute D has a bottom 143 mounted on I-beams 145 and 147 so as to be inclined downwardly in the direction of travel of the wire-bars. The wire-bars slide down the chute D as indicated by the arrow 149, guard plates 151, 151 at the sides of the chute assuring the wire-bars being retained on the chute. The wire-bars may collect at the lower end of the chute as indicated by the dotted lines in Figs. 1 and 2.

Now the conveyor A is being driven from the motor 63. The dogs 23 are in alignment transversely of the conveyor A, so that as the conveyor chains 21 are operated, three of the dogs 23 simultaneously engage a wire-bar, since the discharge end of the chute overhangs the tail end of the conveyor A. For this purpose, the tail end of the conveyor A may be positioned in a sump 153.

The wire-bars may be picked up by the dogs 23 in the manner indicated in Fig. 1. However, as they are moved upwardly, their ends engage the lateral guides 29 and 31 and the bars are shifted thereby until their ends come into alignment; and in this manner they are transferred onto the conveyor B.

The shifting of the bars is facilitated by the rounded surfaces 25 of the dogs 23; and because of the fact that the dogs 23 are spaced at equal distances on the conveyor chains of conveyor A, the bars will be substantially equally spaced on the conveyor B. Conveyor B is operated at a comparatively slow speed so that the bars may be readily inspected as they pass along, and are readily accessible to the chippers during their passage.

As the wire-bars move along the conveyor B as indicated by arrow 155, the inspectors are able to mark the bars to be rejected. As the bars near the discharge end of the conveyor B they pass over the selector conveyor C, the rollers 65 of which are below the path of travel of the wire-bars. Now, as a bar 21a, for example, which has been designated by the inspectors as a "reject" passes over the selector conveyor C, the valve 115 is manipulated by an operator so as to elevate the conveyor C to lift the said bar off of conveyor B, the bar passing by gravity end-ways along the rollers 65 until it strikes a stop plate 157, suitable retaining and guide plates 159 being positioned on angles 67 to assure the bars being retained on the conveyor as they move to the stop plate. It will thus be seen that the rejected bars may be easily removed and separated from the good bars.

By the time the next bar coming along the conveyor B reaches the conveyor C, the operator has lowered conveyor C to its inoperative position. As he does so, the separated bar is lowered across the conveyor chains 69, 69 of the short secondary conveyor F, which chains are operated in conjunction with the main conveyor by the common drive sprocket 55 and the common drive shaft 51. The rejected bars therefore are brought to a single discharge position as at 160, where they may be readily removed; and also the good bars are collected in one location, as indicated at 161, from which they may be removed together by the usual apparatus employed for the purpose.

It will be seen, therefore, that the mechanism of this invention provides means for enabling expeditious inspection and dressing of the castings to be performed, and also means for effecting a ready separation of rejected castings from those passing inspection, all while minimizing the hazards incident to manual handling of the castings.

For the sake of nomenclature, the conveyor A may be considered to be a gathering conveyor, the conveyor B to be an inspection conveyor, the conveyor C to be a separator or selector conveyor, and the conveyor F as a secondary conveyor.

It will be seen that at the discharge end of the conveyor F, the rejected bars are discharged onto the beams 163, collecting thereon as the removal point; and similarly the accepted bars pass from the conveyor B onto the beams 165, all of which beams are suitably supported by the conveyor frame. In its broader aspects, therefore, the invention comprises a conveying mechanism along which articles are adapted to be moved, the mechanism comprising a gathering conveyor, an inspection conveyor, and a separator conveyor, the separator conveyor being normally inactive and out of the path of travel of the articles being moved, and mechanism for actuating the separator conveyor to bring it into active position in engagement with predetermined selected articles for diverting the selected articles from the remainder of the said articles and for conveying the said selected articles to a point of discharge remote from the point of discharge of the said remaining articles. At both discharge points the articles are assembled in alignment for further handling in groups, the aligned assembling of the articles facilitating the rapid removal thereof in their respective assorted condition.

It may be noted that the air cylinder 103 is pivotally secured to angles 160 which angles 160 are welded to angles 83, this pivoted mounting of the air cylinder being indicated by pin 162, extending through a lug 164 on the bottom closure of the cylinder; also wear plates 166 may be provided in the conveyor guide channels 91, 91, and wear plates 167 may be positioned also in the guide channels 168 of the conveyor A.

What is claimed is:

1. A conveying system for the inspection of copper wire-bars, comprising an inspection conveyor adapted to receive the bars laid transversely thereon and along which the wire-bars are adapted to be moved, a gravitationally operated selector conveyor intersecting the inspection conveyor, a pivotal mounting for the selector conveyor at one end thereof, fluid pressure actuated lifting mechanism for the selector conveyor operable responsively to the will of an operator for lifting the said selector conveyor into a tilted operative engagement with selected wire-bars for diverting the selected wire-bars from the remaining wire-bars, and to allow the selected wire-bars to pass lengthways by gravity down the selector conveyor, the said lifting mechanism comprising a pneumatic cylinder including a lifting piston pivotally connected with the selector conveyor, air lines connected with the cylinder for introducing air-pressure therein to effect operation of the piston, and a control valve for the air lines for predeterminedly directing air flow through the cylinder, and mechanism for depositing the wire-bars crossways on the inspection conveyor for inspection and chipping operations and at sufficiently spaced intervals for

- enabling operation of the selector conveyor by removing any selected bars from the inspection conveyor without interruption to the operation of the inspection conveyor.

5. 2. Inspection apparatus for copper wire bars comprising, in combination, an inspection table comprising a main conveyor adapted to receive the wire bars laid transversely thereof in substantially equi-spaced relation, a selector gravity conveyor intersecting the said main conveyor, pivotal mounting means at the foot of the selector conveyor enabling the said selector conveyor to be rotated vertically upon the pivotal mounting between operative and inoperative positions, the said selector conveyor having its receiving end free, fluid-pressure actuated lifting mechanism connected to the selector conveyor for lifting the same about its pivotal mounting and into tilted operative position in engagement with pre-selected wire bars on the main conveyor for lifting a pre-selected wire-bar from the main conveyor onto the selector conveyor without interference with the wire bars on the main conveyor while allowing the wire-bars to pass lengthwise along the selector conveyor, and a secondary conveyor intersecting the selector conveyor for removing from the selector conveyor the wire bars thereon responsive to the return of the selector conveyor to inoperative position.

30. 3. Inspection apparatus for copper wire bars comprising, in combination, an inspection table comprising a main conveyor adapted to receive the wire bars laid thereon transversely across the conveyor in substantially equi-spaced relation, a vertically pivoted selector conveyor, the selector conveyor being normally inactive and below the path of travel of the wire bars being moved along the inspection table, quick-acting mechanism for actuating the separator conveyor to elevate one end of it in sloping operative position in a plane intersecting the plane of the inspection table and in engagement with pre-selected wire bars for lifting a pre-selected bar from its place on the main conveyor and conveying the said bar to a discharge point remote from the discharge of the main conveyor, and means for operating the elevating mechanism of the separator conveyor to shift the latter in a complete cycle between operative and inoperative positions, the separator conveyor being timed to effect removal of any selected bar and to return to inoperative position without interference with the operation of the main conveyor or without interference with the movement with the main conveyor of the succeeding bar thereon.

55. 4. Inspection apparatus for copper wire bars comprising, in combination, an inspection table comprising a main conveyor adapted to receive the wire bars laid thereon transversely across the conveyor in substantially equi-spaced relation, a vertically pivoted gravity selector conveyor, the selector conveyor being normally inactive and below the path of travel of the wire-bars being moved along the inspection table, quick-acting mechanism for actuating the separator conveyor to elevate one end of it into sloping operative position in engagement with pre-selected wire-bars for conveying by gravity the said pre-selected wire-bars to a point of discharge remote from the point of discharge of the main conveyor without interference with the wire-bars during their travel along the inspection table, and means for operating the elevating mechanism of the separator conveyor to shift the latter between operative and inoperative positions.

5. Inspection apparatus for copper wire-bars comprising, in combination, an inspection table comprising a main conveyor adapted to receive the wire bars laid cross-ways thereon, a pivotally mounted selector conveyor, the selector conveyor being normally inactive and below the path of travel of the wire bars being moved along the inspection table, pivotal mounting means at one end of the selector conveyor enabling the selector conveyor to be rotated vertically upon the pivotal mounting between operative and inoperative positions, the said selector conveyor having free its end opposite to the pivotal mounting, pneumatic lifting mechanism connected to the selector conveyor for lifting the same about its pivotal mounting and into tilted operative position in engagement with pre-selected wire bars on the main conveyor for diverting the said pre-selected wire-bars from the main conveyor to the selector conveyor, and means at an inspection station for controlling air pressure to the said pneumatic lifting mechanism for operating the selector conveyor.

6. Inspection apparatus for copper wire-bars comprising, in combination, an inspection table comprising a main conveyor adapted to receive the wire-bars when laid cross-ways thereon, a pivotally mounted gravity selector conveyor, the selector conveyor being normally inactive and below the path of travel of the wire-bars being moved along the inspection table, pivotal mounting means at one end of the selector conveyor enabling the selector conveyor to be rotated vertically upon the pivotal mounting between operative and inoperative positions, the said selector conveyor having free its end adjacent to the main conveyor, the said selector conveyor comprising spaced sections, one of which spaced sections is adapted to engage pre-selected wire-bars when the selector conveyor is in operative position to lift the said wire-bars from the main conveyor onto the selector conveyor, the said bars travelling by gravity in lengthwise direction along the said selector conveyor, frame members interconnecting the said sections to form a rigid structure, an auxiliary conveyor interposed between adjacent sections of the selector conveyor for removing the wire-bars from the selector conveyor as the latter returns to inoperative position, and an abutment member for stopping movement of the wire-bars at the foot of the selector conveyor.

7. A conveyor system for facilitating inspection of copper wire-bars comprising, in combination, an inspection conveyor having an inspection station, means for depositing the wire-bars transversely of the inspection conveyor at substantially regular intervals on the conveyor sufficient to enable ready inspection of the said bars, a selector conveyor positioned in a plane intersecting the plane of the inspection conveyor, but normally below the level of the inspection conveyor and hence normally below the path of travel of the wire-bars being inspected, means for pivotally mounting the selector conveyor at one end thereof remote from the inspection conveyor for vertical movement into inclined position intersecting the said path of travel of the wire-bars whereby pre-selected bars may be diverted from the remaining bars by the selector conveyor and allowed to pass lengthwise along the selector conveyor, fluid-actuated quick-lifting devices beneath the free end of the selector conveyor for operating the said conveyor to raise and lower the same between inoperative and op-

erative positions, and fluid-pressure control means operable at the inspection station enabling quick actuation of the lifting devices for quickly shifting any selected bars from the inspection 5 conveyor onto the selector conveyor without interruption to the operation of the inspection conveyor.

8. A conveyor system for facilitating inspection of copper wire-bars, comprising, in combination, an inspection conveyor having an inspection and selector station, means for depositing, transversely of the conveyor, the wire-bars at substantially regular intervals on the conveyor sufficient to enable ready inspection of the said bars, the said 10 conveyor comprising a frame defining tracks, endless conveyor devices mounted on the tracks on which devices the wire-bars ride, a selector conveyor positioned in a plane intersecting the plane of the inspection conveyor but normally 15 below the level thereof, the said selector conveyor comprising a frame defining a plurality of spaced sections and frame members interconnecting the sections, conveyor instrumentalities for the sections, means for pivotally mounting 20 the conveyor frame at its end remote from the inspection conveyor, the said frame having its other end free for enabling movement thereof into operative engagement of the conveyor instrumentalities thereon with pre-selected wire- 25 bars on the inspection conveyor whereby the pre-selected bars may be diverted from the remaining bars by the selector conveyor, quick-acting fluid-pressure actuated lifting devices beneath the free end of the selector conveyor for operating 30 the said conveyor to raise and lower the same between horizontal inoperative and inclined operative positions so that the said pre-selected bars may pass along the said selector conveyor from the inspection conveyor, and fluid-pressure control 35 means operable at the inspection station enabling quick actuation of the lifting devices for quickly shifting any pre-selected bars from the inspection conveyor onto the selector conveyor without interruption of the progress of the 40 remaining bars on the inspection conveyor.

9. Inspection apparatus for copper wire bars comprising, in combination, an inspection table comprising a main conveyor adapted to receive wire-bars laid thereon, mechanism for depositing wire-bars on the inspection table transversely 45 thereof at regular spaced intervals, a selector conveyor normally inactive and positioned below the path of travel of the wire-bars being moved along

the inspection table, means for lifting one end of the selector conveyor beneath a pre-selected wire-bar sufficiently to remove the said pre-selected bar from the main conveyor and to cause the said bar to pass lengthwise down the selector conveyor without interruption to the movement of the main conveyor, the said bar-depositing mechanism spacing the wire-bars on the inspection conveyor at sufficiently spaced-apart intervals for enabling the selector conveyor to move from 10 inoperative to operative position for removal of the selected bar and to return to inoperative position before arrival of the succeeding bar at the location of the selector conveyor.

10. Inspection apparatus for copper wire-bars comprising, in combination, an inspection table comprising a main conveyor adapted to receive wire-bars laid thereon, mechanism for depositing wire-bars on the inspection table transversely thereof and at regular spaced intervals, a selector conveyor normally inactive and positioned below the path of travel of the wire-bars being moved along the inspection table, a pivotal foot mounting for the selector conveyor enabling the receiving end of the said selector conveyor to be 15 raised beneath a pre-selected wire-bar on the main conveyor sufficiently to remove the said pre-selected bar from the main conveyor without interruption to the movement of the main conveyor and to cause the said bar to coast down 20 the selector conveyor, fluid-pressure actuated mechanism for shifting the receiving end of the selector conveyor between inoperative and operative positions, the said bar-depositing mechanism spacing the wire-bars on the inspection 25 conveyor at sufficiently spaced-apart intervals for enabling the selector conveyor to move from inoperative to operative position for removal of the selected bar and to return to inoperative position before arrival of the succeeding bar at 30 the location of the selector conveyor while allowing the selector bar to pass lengthwise along the conveyor, and means for controlling actuation of the said fluid-pressure actuated mechanism for causing the said selector conveyor to shift 35 sufficiently quickly from inoperative position to operative position and back to inoperative position to remove any pre-selected bar from the main conveyor without interruption to the movement of the main conveyor or the succeeding 40 wire-bar.
